UNITED STATES PATENT OFFICE.

MICHAEL PARIDON, OF OSWEGO, NEW YORK, ASSIGNEE TO THE DIAMOND MATCH COMPANY, OF CHICAGO, ILLINOIS, A CORPORATION OF ILLINOIS.

TAKE-OFF MECHANISM FOR MATCH-MACHINES.

1,252,941.

Specification of Letters Patent.

Patented Jan. 8, 1918.

Application filed April 16, 1915. Serial No. 21,632.

To all whom it may concern:

Be it known that I, MICHAEL PARIDON, a citizen of the United States, and resident of the city and county of Oswego and State 5 of New York, have invented certain new and useful Improvements in Take-Off Mechanism for Match-Machines, of which the following is a specification.

This invention relates to take-off mechanism for match machines, having reference 10 more particularly to that type of mechanism in which is employed a conveyer having spaced guiding and partitioning blades for the matches, the distance between adjacent 15 blades being less than the length of a match. Such conveyers are used for partitioning and impelling the commercial match boxes in those machines in which the matches are delivered to the boxes directly from a match 20 machine, and they are also used for feeding the matches in an orderly manner through a take-off trough in those machines in which the matches are delivered in bulk to the trough.

As heretofore constructed the blades were 25 substantially rectangular plates, the upper projecting edges of which in their travel across the path of the falling matches from the match machine presented horizontal 30 supports to the matches; and hence in the event of some of the matches during their rapid discharge from the carrier becoming awry and dropping longitudinally or diagonally, instead of transversely, of the di- 35 rection of movement of the conveyer, the ends of such matches rested on the adjacent plates instead of falling into the space between the plates; thus interfering with the uniform and orderly delivery of the matches 40 to the boxes or to the trough, as the case might be.

According to my invention I so fashion the upper edges of the blades that they 45 present to falling awry matches, cam surfaces which serve efficiently to deflect such matches into the underlying spaces between the proximate blades, and thus permit a more rapid travel of the chain than formerly, as will be hereinafter described and 50 claimed.

In the drawings—

Figure 1 is a longitudinal section of a 55 part of a match take-off conveyer embodying a preferred form of my invention; the same being illustrated as mounted to travel

along the take-off trough of a match machine, a part of the match carrier of the match machine also being indicated.

Fig. 2 is a transverse section through the conveyer and adjuncts, as on the line 2—2 60 of Fig. 1.

Fig. 3 is a perspective view of a pair of connected links of the conveyer, indicating in dotted lines an awry match as intercepted 65 in its descent by the blades of the links.

4 is a horizontal trough supported at and transversely of the discharging end of a match machine on a plane below the path of discharge of the matches from the carrier plates 5, which trough in the form shown is 70 designed to receive the matches row by row as rapidly as they are discharged. This trough is slidably supported upon guide blocks 6 rising from a suitable bed 7, and is given a longitudinal reciprocating or jar- 75 ring motion in any suitable manner in order to agitate the contained matches and cause them to settle compactly within the trough. The trough is also provided with a yielding 80 spring bottom plate 8 and also along the upper inner edges of its side walls with parallel guide flanges 9.

Passing through the trough, in contact 85 with the guide flanges 9, is the horizontal run of an endless conveyer 10 which is pro- 90 vided with regularly-spaced transverse blades 11, the distance between adjacent blades being less than the length of a match. This conveyer passes around curved guide pieces 12 (of which one only is shown) be- 95 yond the respective ends of the trough, and also around a pair of overlying guide wheels whereof one is appropriately geared with and continuously driven from a drive shaft. As the present invention particularly con- 100 cerns the blade construction of the conveyer it is deemed unnecessary herein to show the conveyer in its entirety or to illustrate in detail its supporting and driving mecha- nisms.

In this connection reference may be had to Patents No. 538,535 dated April 30, 1895, and No. 1,016,436 dated February 6, 1912.

In pursuance of my invention and as an 105 exemplification of its principle I oppositely bevel the upper edges of the blades and deflect the beveled portions laterally as shown; that is to say, I make the upper projecting portion 13 of each blade in the form of an inverted V, and then slightly bend such 110

portion laterally to provide an inclined triangular member whereby the basal portion merges with the body of the plate. Hence matches falling diagonally from the match carrier impinge at or near their ends upon the oppositely-inclined edges of the adjacent blades respectively, and being thereby swung or cammed around are directed into the space between the blades; that is to say, assuming a splint to fall diagonally across the space as indicated in Fig. 3, the headed part of the splint contacts with the outer inclined surface of one of the blades and the other end of the splint impinges upon the inner inclined edge of the adjacent blade, and as the heavier or headed end of the splint naturally rolls down the opposing incline the other end of the match is cammed inwardly by the inclined edge opposed thereto, the resultant movement of the match tending to deflect it bodily into the space between the blades. Thus the chain may be efficiently impelled at a higher speed than formerly.

25 Although the blades may be separate members attached to the links of the conveyer, I prefer to construct each blade as an integral part of a link, as best seen in Fig. 3, that is to say, the side members of each link 30 and the transverse blade connecting them are struck up from a single piece of sheet metal with suitably-disposed eyes for the pivot rivets formed in the side members.

I claim as my invention—

35 1. In take-off mechanism for match machines, the combination with a match carrier and a trough at the discharging portion thereof, of a conveyer movable along said trough having blades at intervals apart directly beneath the path of awry unrestrained matches falling from the match carrier, the distance between adjacent blades being less than the length of a match and the upper portions of adjacent blades being 40 formed to present match-deflecting inclines descending longitudinally of the blades in

opposite directions to each other, whereby falling awry matches alighting upon such inclines are caused to swing bodily and fall into the space between the blades. 50

2. In take-off mechanism for match machines, the combination with a match carrier and a trough at the discharging portion thereof, of a conveyer movable along said trough having blades in spaced relation to each other directly beneath the path of awry unrestrained matches falling from the match carrier, the distance between adjacent blades being less than the length of a match, and the upper edge of each blade 60 being formed to present two match-deflecting inclines descending longitudinally of the blade to the respective ends of the blade, whereby falling awry matches alighting upon the reversely disposed inclines of adjacent blades are caused to swing bodily and fall into the space between the blades. 65

3. In take-off mechanism for match machines, the combination with a match carrier and a trough at the discharging portion thereof, of a conveyer movable along said trough having blades at intervals apart, the distance between adjacent blades being less than the length of a match and the upper edge of each blade being formed to present 70 two match-deflecting inclines descending longitudinally of the blade to the respective ends of the blade, said upper edge also being laterally deflected. 75

4. A match conveyer having blades thereon at intervals apart, the distance between adjacent blades being less than the length of a match and the upper edge of each blade being formed to present two match-deflecting inclines descending longitudinally of the 80 blade to the respective ends of the blade, said upper edge also being laterally deflected. 85

Signed at the city and county of Oswego, and State of New York, this 12th day of April, A. D. 1915.

MICHAEL PARIDON.
